BELT SANDER

Marnie C. Averitt, Timonium, Md., assignor to The Black and Decker Manufacturing Company, Towson, Md., a corporation of Maryland

Filed Oct. 18, 1965, Ser. No. 87,551

Term of patent 14 years

(Cl. D37—1)

FIG. 1

FIG. 2

FIGURE 1 is a perspective of the belt sander;
 FIGURE 2 is another perspective, taken from the other side of the tool, and showing the belt and its pulleys in broken lines;

FIGURE 3 is a side elevation;
 FIGURE 4 is a top plan view;
 FIGURE 5 is a bottom plan view, the blank space indicating the belt;

FIGURE 6 is a side elevation viewed from the side opposite to that of FIGURE 3;

FIGURE 7 is a front elevation; and

FIGURE 8 is a rear elevation.
 The dominant features of my design reside in the portions shown in full lines.

I claim:

The ornamental design of a belt sander, as shown and described.
